UNITED STATES PATENT OFFICE.

ANISE F. FRAME, OF SOUTH CHARLESTON, WEST VIRGINIA.

APPARATUS FOR REMOVING CHEMICALS FROM SOLIDS AND SEMISOLIDS.

Application filed November 14, 1921. Serial No. 515,125.

To all whom it may concern:

Be it known that ANISE F. FRAME, a citizen of the United States, residing at South Charleston, in the county of Kanawha and State of West Virginia, has invented certain new and useful Improvements in Apparatus for Removing Chemicals from Solids and Semisolids, of which the following is a specification.

10 This invention has relation to certain new and useful improvements in an apparatus for extracting chemicals from solids and semi-solids and has for its primary object the provision of an apparatus of the 15 character stated which will be especially designed for extracting alcohol from wood and the like without a mixture of the dust within the extracted chemicals.

The invention has for an object the provision of an apparatus similar to a retort and constructed in such a manner that alcohol may be readily extracted from wood fed into and working through the cylinder of the apparatus in powdered form without 25 the powdered material mixing with the extracted alcohol vapor and passing from the cylinder with said vapor.

A further object of the invention resides in the provision of an apparatus of the 30 character set forth which will include a stationary inclined cylinder mounted in a proper supporting structure and having an automatically cooled feeding screw working in the lower portion of the inclined cylinder 35 to carry through the cylinder the powdered material from which the chemical is to be extracted under influence of the heat directed to the lower side of the cylinder from the burners positioned beneath the 40 same and within the supporting structure for the cylinder.

The invention has for a still further object the provision of an apparatus of the character stated in which the operative 45 parts may be readily controlled and the feeding screw prevented from overheating and thereby interfering with proper operation of the apparatus.

50 The invention has for still another object the provision of an apparatus of the character stated in which may be included automatic feeding means to feed the material into the upper portion of the cylinder and at the same time maintain an airtight 55 enclosure between this primary feeding mechanism and the stationary cylinder to

prevent the extracted chemicals or vapors from passing back to the feed hopper.

The invention has for a still further object the provision of an apparatus of the 60 character set forth in which the extracted chemicals in the form of vapors may be properly discharged from the cylinder and conducted to the condenser in a pure form and without carrying a dust or powder 65 from the cylinder.

With the foregoing and other objects in view as will appear as the description proceeds, the invention consists in the novel construction, combination and arrangement 70 of cooperating elements as hereinafter more specifically set forth, claimed and shown in the accompanying drawings forming a part of the present application and in which:—

Figure 1 is a side elevation of the complete apparatus constructed in accordance with this invention.

Figure 2 is a vertical longitudinal section through the apparatus.

Figure 3 is an end elevation, looking at the rear or upper end of the apparatus.

Figure 4 is a vertical sectional detail view on an enlarged scale, substantially on the plane of line 4—4 of Fig. 1, looking in 85 the direction indicated by the arrows.

Figure 5 is a vertical sectional view on the plane of line 5—5 of Fig. 2, looking in the direction indicated by the arrows.

Figure 6 is a detail sectional view substantially on the plane of line 6—6 of Fig. 4, looking in the direction indicated by the arrows.

Figure 7 is an enlarged sectional detail view showing the mounting of the forward 95 or lower end of the feed screw.

Figure 8 is a similar view, showing the mounting of the upper end of the feed screw and the pulley carried by the extended upper rear end of said feed screw.

Figure 9 is a detail section, showing the structure of the discharge end of the apparatus.

Referring more in detail to the drawings 105 in which similar reference characters designate corresponding parts throughout the several views, 1 indicates the supporting base which may be of concrete or any other suitable construction and upon which is mounted a supporting structure 2 of brick, concrete or any other form for enclosing 110 and properly supporting the forwardly and

downwardly inclined stationary cylinder 3 and extended longitudinally therethrough, as shown clearly in Figs. 1 and 2 of the drawings. Figure 5 will also show clearly 5 that the structure 3 includes pillars 4 for the cylinder 3 to rest upon. These pillars 4 may be located at the ends of the structure 2 or at any other suitable points therein. Extending longitudinally of the space 5 in 10 the lower portion of the supporting structure 2, are the burner carrying tubes 6 connecting with a gas supply pipe 7 or the like extended through one end of the supporting structure 2 for feeding combustible fuel 15 to the burners 8 mounted on the burner carrying rods 6. Each rod 6 carries a plurality of burners positioned beneath the opposite side portions of the cylinder 3, as shown clearly in Fig. 5. The purpose of 20 arranging the burners in this manner will presently appear. It will also be seen that the burner carrying tubes 6 are inclined to correspond with the incline of the stationary cylinder 3. This cylinder 3 has a closed 25 upper end 9 and a removable lower end 10. The cylinder 3 also has an inlet opening 11 on one side, preferably below the center thereof and near the upper end of the cylinder 3. An upwardly directed chemical 30 liquid or fuel conducting pipe 12 is also carried near the upper end of the cylinder 3 and leads to a condenser, not shown. A discharge tube 13 depends from the lower end portion of the cylinder 3, outwardly of 35 the supporting structure 2, to discharge the waste product or by product of the apparatus from this end of the cylinder 3, as will be readily understood by referring to the drawings.

40 For feeding material through the cylinder 3, a screw feed shaft 14 is provided and extending through the bottom or lower portion of the cylinder 3 and through the ends 9 and 10 thereof. This shaft carries the spiral feed screw 15 working in the lowermost portion of the cylinder 3 and extending the entire length thereof, as clearly shown in Fig. 2. The shaft 14 has its upper end extended into the stationary bearing 16 carried on the upper shaft supporting standard 17. This upper end of the shaft 14 is adapted to rotate within the stationary bearing 16 and carries a rigid belt wheel 18 spaced between the bearing 16 and the spacing collar 19, as shown in Fig. 8. The beveled wheel 18 may be keyed to the shaft 14 or secured thereon in any other suitable and well known manner and is adapted to be driven to cause rotation of the shaft 14, by means of a drive belt 20 extended around said belt wheel 18. A suitable packing member 21 may be carried by the upper end 9 of the cylinder, around the upper end portion of the hollow shaft 14 to form an air-tight connection at this point. Suitable 45 packing members 22 may also be located in the stationary bearing 16 between the ends of the shaft 14 and the water pipe section 23. This water pipe section 23 has one end curved and extended into the stationary bearing 16, as shown in Fig. 8 so as to provide for the feeding of water or other cooling fluid through the hollow shaft 14, as will be later clearly understood. The opposite or lower end of the shaft 14 is shown 50 as being slightly reduced and extended through the bearing sleeve or collar 10' carried by the lower removable head 10 of the cylinder 3. This sleeve or collar 10' has a bearing cup or similar member 24 threaded thereon or secured thereto in any other suitable and well known manner. This member 24 is provided for holding the turned end 55 of the water pipe section 25 having communication with the lower end of the shaft 14, as clearly shown in Fig. 7. Suitable packing members 26 may also be provided in the member 24 at the ends of the shaft 10 and the pipe section 25. It will be evident that the pipe sections 23 and 25 may 60 be connected with any suitable source of supply and discharge for the cooling fluid so as to provide for a continual flow of the cooling fluid through the hollow shaft 14 to keep this feed screw carrying shaft and the screw formed thereon from becoming overheated during operation of the device, and thereby increase the efficiency thereof. In order to feed the material into the stationary cylinder 3, I have provided a feed member 27 of conventional form and having its reduced lower end mounted on a fuel conveying tube 28 extended substantially 65 parallel with the stationary cylinder 3 and connecting with a second tube 29 at a right angle thereto and of a larger diameter. The tube 28 connects with the tube 29 near the outer end of the latter while the inner end of the tube 29 extends into the side of the stationary cylinder 3, adjacent the upper end thereof and preferably forwardly or ahead of the vapor projecting pipe 12. The hopper 27, pipes 28 and 29 are also located 70 near the lower side of the stationary cylinder 3 and in a plane slightly above the plane of the feed screw shaft 14 and spiral feed screw 15 of the stationary cylinder 3. Suitable supporting and bracing means may be provided for the tube 28 and the tube 29 as well as the hopper 27, as shown at 30 in 75 Figs. 1, 4 and 6. It is also to be noted that a spiral feed screw 31 extends practically the entire length of the tube 28 to feed the material deposited therein from the hopper 27 to the tube 29, as shown clearly in Fig. 6, as well as Fig. 4. The shaft 32 of the feed screw 31 extends out of the outer end of the tube 28 and has a pulley or belt wheel 33 mounted thereon to be operated by a belt 80 34 extended around the same, as shown 85 90 95 100 105 110 115 120 125 130

clearly in the drawings. This will provide for a continual feeding of the material to the tube 29.

As means for feeding properly the material or fuel through the tube 29 and into the stationary cylinder 3, I have provided a plunger 35 working in the greater portion of the tube 29 and passing opposite the end of the tube 28 on each stroke, thereby forcing the material or fuel into the cylinder 3, as shown in Fig. 4 of the drawings. The plunger 35 is operated by the pitman rod 36 connected thereto in a suitable manner, as shown in the drawings and also connected with the crank portion 37 of the crank shaft 38 mounted in suitable bearing and supporting means 39, as shown in Fig. 4. The crank shaft 38 carries a suitable belt wheel 40 with the driving belt 41 extended around the same to operate the crank shaft 38 and thereby reciprocate the plunger 35 within the tube 29. It is evident that by feeding the fuel into the stationary cylinder 3 in this manner, it will be impossible for air or gas to pass into or out of the stationary cylinder 3 by way of the feed tube 29.

By referring to Fig. 9 of the drawings, it will be seen that the cross pipe 42 is mounted on the depending discharge pipe 13, at the lower end of the latter and the discharge plunger 43 reciprocates in the cross pipe 42, beneath the pipe 13. This plunger or piston 43 is operated by the pitman arm 44 pivotally connected therewith and carried by the crank portion 45 of the crank shaft 46. This crank shaft 46 is mounted in suitable bearings at one end of the cross pipe 42 and carries a belt wheel or pulley 47 operated by the belt 48 extended therearound and connected with any suitable source of power, not shown. It is evident that the plunger or piston 43 will serve to force the by-product or waste product from the discharge end of the cross pipe 42 without permitting air to enter the cylinder 3 by way of the discharge pipe 13.

From the foregoing description taken in connection with the accompanying drawings, the complete construction and operation of the apparatus may be readily understood without further detailed description. It may be stated, however, that the various driving belts may be connected with any suitable source of power to properly drive the shafts of the apparatus. It is also evident that the supply of fuel to the burners on the burner pipe may be readily regulated so as to provide for the proper heating of the contents of the stationary cylinder 3. The passage of water or other cooling fluid

through the hollow feed screw shaft 14 will prevent overheating and bending of this shaft and the feed screw 14 while working 65 the fuel or other material towards the lower end of the stationary cylinder 3. By providing a stationary cylinder 3 and the feed screw 15 in the lower portion thereof with the other parts arranged as described, the 70 chemicals extracted from the fuel during the operation of the apparatus, in the form of vapors or gases may readily pass through the pipe 12 to the condenser, not shown, without carrying therewith portions of the 75 fuel in partially consumed or powder form or in any other form. It is therefore evident that pure vapors or gases may be obtained by the use of this apparatus while the used fuel or material may be discharged from the stationary cylinder 3 by means of the discharge pipe 13, as will be apparent by referring to Figs. 1 and 2 of the drawings. By reference to Fig. 9, it will also be evident that the material after passing 80 through the cylinder 3 may be discharged therefrom without danger of air entering the discharge end of the cylinder 3.

While the preferred embodiment of the invention has been shown and described, it is to be understood that minor changes in the details of construction and arrangement of parts may be resorted to within the scope of what is claimed without departing from 90 the spirit of the invention.

What I claim is:—

An apparatus of the class described, a stationary cylinder, a rotatable feed screw working in the lower portion of said cylinder and extending longitudinally thereof, a supporting structure for said cylinder, a feed hopper, a plurality of feed pipes connected to one another, one of said pipes receiving material from the hopper, another of said pipes serving to deliver the material to the upper end portion of the feed screw within said stationary cylinder, the first mentioned pipe connecting with the central portion of the second mentioned pipe, a spiral operating feed screw extending through said first mentioned pipe to provide for a constant feeding of the material to the second pipe, means for operating the last mentioned feed screw, a reciprocating feeding mechanism in the second mentioned pipe to cut off communication between the first and second mentioned pipes as the material is forced into said cylinder, and means for operating the reciprocating feeding 100 mechanism. 105 110 115 120

In testimony whereof I affix my signature.

ANISE F. FRAME.
